E. O. BIDDLE

WINDOW GUARD

Filed Nov. 6, 1922

INVENTOR:

Earl O. Biddle.

BY Arthur H. Ewald,

ATTORNEY.

UNITED STATES PATENT OFFICE.

EARL O. BIDDLE, OF WYOMING, OHIO.

WINDOW GUARD.

Application filed November 6, 1922. Serial No. 599,331.

My invention relates to a guard for a window whereby access to the interior of a building thru the protected window when the lower sash thereof is raised is prevented.

5 The present invention has for its principal object the provision of a simple, inexpensive and convenient window guard of the character above mentioned.

10 A further object of the invention is to provide a window guard of the nature mentioned, which may be lowered when the window is closed so as to be out of the way, thus leaving the window entirely unobstructed and accessible.

15 A further object of this invention is to provide in a window guard a framework composed principally of protecting bars, said bars being individually secured to the window structure, whereby the entire framework is more securely affixed and the loosening of the fastenings of one or more bars does not destroy the protective nature of the device.

20 Further objects of the invention will appear from the following detailed description thereof.

In the drawings:

25 Figure 1 is a sectional view of a portion of a window provided with a guard constructed in accordance with this invention;

30 Figure 2 is a perspective of a portion of the guard framework;

Figure 3 is a side elevation of one of the protective bars;

35 Figures 4, 5 and 6 are perspective views of the various attaching and securing members.

In the drawings the numeral 1 indicates the inner sill of a window, below which is 40 the usual apron 2. The lower and upper window sashes are indicated by the numerals 3 and 4 respectively.

45 My new window guard consists principally of protective bars 5 which may be of cast metal or other suitable construction. Each of said bars has an intermediate substantially horizontal section 6 adapted to rest on the surface of the window-sill; from the horizontal section 6 the bar is provided 50 with a downwardly and inwardly bent section 7 terminating in a crook 8. Each of the bars is provided on its two lateral faces with grooves 9, the lower ends of which are widened and open on the inner edge of the bar as shown at 10. The upper ends of the

grooves terminate below the upper ends of the bars. The under side of the horizontal portion 6 of each of the bars is provided with a notch 11.

55 The protective bars above described are secured to the window frame and sash by means of attaching members shown in Figures 4, 5 and 6 respectively.

60 Secured to the apron 2 of the window frame are brackets 12, one being provided for each of the bars 5. Said brackets are

65 preferably of rectangular metal construction and have screw holes 13 in their attaching sides, the other sides being provided on their lower edges with notches 14. The 70 crooks 8 of the bars are inserted thru the central openings in the brackets, and said crooks rest in the notches 14 when the bars are in position as shown in Figure 1; when in such position the heads of the attaching 75 screws are protected so that the brackets cannot be removed. On the upper surface of the sill 1, plates 15 are provided, one

80 for each bar, said plates being attached by means of screws thru perforations 16. The 80 plates have upwardly extending side flanges

85 17 adapted to abut against the sides of the bars above the notches 11, said notches engaging over the middle portions of the plates. Mounted on the lower bar of the lower window sash 3 are plates 18, one being provided for each of the bars 5. The plates 18 are

85 secured by means of screws thru perforations 19. Said plates are provided with flanges 20 which terminate in inwardly 90 turned fingers 21. The fingers 21 are arranged to engage and slide in the grooves 9 of the bars and to secure the bars in vertical position when the lower sash is raised as

95 shown in Figure 1. When the bars are in 95 raised position the screws used in attaching plates 15 and 18 are protected against access thereby. Cross-bars 22 in any suitable number may be secured to the bars 5 by means of screws, for assembling the bars 5 100

105 into a composite framework.

To attach a window guard as above described, the window frame and lower sash are provided with brackets 12 and plates 15 and 18 secured to the various structures as above set forth. Individual bars 5, or a composite framework composed of such bars and cross-bars 22, may then be placed for use by inserting the crooks 8 of the bars in the brackets 12. When it is desired to use 110

the guard the lower sash is closed and the bars are raised, individually or as a frame when assembled with bars 22, so that the horizontal sections 6 rest on the sill, the notches 11 engaging over the plates 15 between the flanges 17. The open portions 10 of the grooves 9 permit the lower portions of the bars to enter between the fingers 21 of the plates 18. When the lower sash is raised, the fingers 21 engage in the grooves 9 thus securing the guard bars in vertical position so as to protect the open portion of the window. The upper ends of the grooves 9 are closed and thus prevent the removal of the fingers 21 by further raising the sash; thus the bars cannot again be lowered until the lower sash is closed and therefore this operation can be accomplished only by a person inside the room.

It will thus be seen that in the construction above described I have provided a simple, inexpensive and effective window guard composed of protective bars each of which is individually secured to the window frame and sash. It will further be seen that when in use the structure is held rigidly in position to protect the open portion of a window, and that to lower the same the operator must be inside the room. When lowered the guard will rest unobtrusively against the inner wall below the window, and may be readily removed entirely when desired merely by lifting the same out of the brackets 12.

Having thus fully described my invention what I claim as new and desire to secure by Letters Patent is:—

1. In a window guard, a protective bar, said bar having a bent horizontal section arranged to rest on the inner sill of a window, means for securing the lower end of said bar below said sill, and means whereby the upper portion of the bar is arranged to interlock slidably with a sash of said window.
2. In a window guard, a protective bar, said bar having a bent horizontal section arranged to rest on the inner sill of a window, means for hingedly securing the lower end of said bar below said sill, and means whereby the upper portion of the bar is arranged to have interlocking slidable engagement with a sash of said window, said means being arranged also to disengage when said sash is closed.
3. In a window guard, a protective bar, said bar having a bent horizontal section arranged to rest on the inner sill of a window, means for hingedly and detachably securing the lower end of said bar below said sill, and means whereby the upper portion of the bar is arranged to have interlocking slidable engagement with a sash of said window, said means being arranged also to disengage when said sash is closed.
4. In a window guard, a protective bar,

said bar having a bent horizontal section arranged to rest on the inner sill of a window, means for hingedly securing the lower end of said bar below said sill, means on said sill arranged to interlock with the section of the bar resting thereon, and means whereby the upper portion of the bar is arranged to have interlocking slidable engagement with a sash of said window, said means being arranged also to disengage when said sash is closed.

5. In a window guard, a protective bar, said bar having a section arranged to rest on the inner sill of a window and being provided with grooves on its lateral faces above said sill section, the lower portions of said grooves being open toward the sash of said window, means for hingedly securing the lower end of said bar below said sill, and means on the sash adapted when the bar is moved on its hinged mounting into protecting position to engage in said grooves when the sash is opened to secure the bar in said position.

6. A window guard comprising a plurality of protective bars, each of said bars having a bent horizontal section arranged to rest on the inner sill of a window, means for hingedly securing the lower ends of said bars below said sill, means whereby the upper portions of the bars are arranged to have interlocking slidable engagement with a sash of said window, said means being arranged also to disengage when said sash is closed, and cross-bars secured to said protective bars.

7. A window guard comprising a plurality of protective bars, each of said bars having a bent horizontal section arranged to rest on the inner sill of a window, means for hingedly and detachably securing the lower ends of said bars below said sill, means whereby the upper portions of the bars are arranged to have interlocking slidable engagement with a sash of said window, said means being arranged also to disengage when said sash is closed, and cross-bars secured to said protective bars.

8. A window guard comprising a plurality of protective bars, each of said bars having a bent horizontal section arranged to rest on the inner sill of a window, means for hingedly securing the lower ends of said bars below said sill, means on said sill arranged to interlock with the section of each of the bars resting thereon, means whereby the upper portions of the bars are arranged to have interlocking slidable engagement with a sash of said window, said means being arranged also to disengage when said sash is closed, and cross-bars secured to said protecting bars.

9. A window guard comprising a plurality of protective bars, each of said bars having a section arranged to rest on the

inner sill of a window and being provided with grooves on its lateral faces above said sill section, the lower portions of said grooves being open toward the sash of said window, means for hingedly securing the lower ends of said bars below said sill, and means on the sash adapted when the bars are

5 moved on their hinged mounting into protecting position to engage in the grooves of said bars when the sash is opened to secure 10 the bars in said position, and cross-bars secured to said protecting bars.

EARL O. BIDDLE.
